[57] CLAIM

The ornamental design for a dining table or similar article, as shown and described.

DESCRIPTION

FIG. 1 is a top plan view of a dining table or similar article embodying my design;

FIG. 2 is a front elevational view of FIG. 1;

FIG. 3 is a left end view of FIG. 2 with the opposite table end being the same in appearance; and

FIG. 4 is a transverse view along line 4—4 of FIG. 2.
